JOHN G. LEWIS, OF ST. LOUIS, MISSOURI.

HEM OR SEAM FOR SEWED ARTICLES.

1,155,360.

Specification of Letters Patent. Patented Oct. 5, 1915.

Application filed June 18, 1909. Serial No. 502,878.

To all whom it may concern:

Be it known that I, JOHN G. LEWIS, a citizen of the United States, residing at the city of St. Louis, in the State of Missouri, have invented a certain new and useful Hem or Seam for Sewed Articles, of which the following is such a full, clear, and exact description as will enable any one skilled in the art to which it appertains to make and use the same, reference being had to the accompanying drawings, forming part of this specification.

My invention relates to a hem or seam for sewed articles to be made by a sewing machine. One of its objects is to provide a seam wherein every loop laid by the needle may penetrate the goods and be appropriately keyed, as by engagement of said loops with a second, keying thread, or by the interchaining of the penetrant loops beyond their points of emergence from the work, so as to form goods-holding stitches, and wherein for every penetrant loop of needle thread so formed there may be provided an overcast loop, or bight, of needle thread, giving to every stitch both an overcast loop and a goods-engaging keyed-loop structure, for an overseaming and a holding effect.

Another object of my invention is so to relate the penetrant and overcast loops of needle thread that each overcast loop, springing from the points of entrance of two successive stitches into the goods, has its bend or crest definitely positioned by laying said bend about the emergent portion of the last-laid one of said stitches for retention in such position by the running connections between points of stitch emergence for the advantages, among others, of certainty of binding effect, retention of the overcast loop against shifting, and uniformity of appearance.

Another object of my invention is to provide a seam of the character described, wherein the course of, and linear extent of, the keying thread structure that makes the running connections between the successive points of stitch-emergence is not materially affected by the provision of the over-seaming loops or bights, so that where a second thread is used to key the penetrant loops of needle thread, the amount of the second thread used may be minimized and so that no slack is needed in the keying thread. Thus in a lock stitch seam so formed, un-

duly frequent replenishment of the bobbin is avoided and it is not necessary that any take-up action be performed on the bobbin thread.

A further object of my invention is to provide a blind stitch felling seam—i. e. a seam in which an edge of a superimposed layer is secured to a subjacent base layer by stitches entering and emerging from the same side of the work and concealed on the "fair" side of the work opposite to that on which the stitching is done,—wherein the display of thread on the "stitched" side of the work, on which the stitching is done, may be minimized, only one thread being caused to cross the edge and the keying thread-structure (which in a two-thread seam may be of different quality or color) being laid substantially parallel with and below the level of the edge of the superimposed layer, so that if exposed at all its exposure may be local to the base layer of fabric, and so that by appropriate relation of the edge line to the row of stitching said portion of the thread lying upon the base layer may be partially or wholly concealed beneath the superimposed edge.

In the drawings wherein, for purposes of full disclosure of my invention, I have illustrated both felling and padding seams, and both lock and chain stitch formations, embodying my invention, Figure 1 is a plan view showing a lock stitch felling seam securing the edge of a superimposed layer of material to a subjacent base layer, wherein the penetrant loops are inclined to the edge; Fig. 2 shows a form of stitch of the same type as Fig. 1—but with the needle piercing the superimposed layer at a small or very acute angle to the edge, and the keying-connections laid wholly beneath the edge. Fig. 3 shows a padding seam, that is to say a seam sewing together face to face two superimposed layers of material. Fig. 4 shows a form of felling stitch embodying my invention and employing a single thread concatenated to form the well known chain stitch. Fig. 5 shows in plan view a felling seam employing two threads concatenated, as to keying arrangement, after the fashion of the well known double-thread chain stitch. Fig. 6 is a section on line 6—6 of Fig. 1.

In Figs. 1 and 2, 10 indicates a base layer

of goods and 11 a superimposed layer, preferably under some conditions having a turned under edge, 19 laid upon the base layer to be felled thereon. In the illustrated views the superimposed layer is provided by a folding back upon itself the base layer, as may be done in a trousers bottom, for example.

The folded edge 19 of the superimposed layer is secured to the base layer by a single row of stitches, comprising a series of keyed penetrant loops, said stitches passing into and out of (but preferably not through) the work as a whole on the same side thereof. 10 Each stitch penetrates through the folded edge portion of the superimposed material and into and out of the proximate surface of the base layer, preferably without showing through to the opposite side of the base 15 layer, so that the stitching will be blind on the fair side of the work. As shown in each of said views, the needle thread 12 is passed, upon each reciprocation of the needle, into the superimposed goods at 14 and through 20 the superimposed goods into the main layer, and out of the main layer at 15 under or adjacent to the folded edge, all on the same side of the work, each said penetrant loop being keyed for retention in suitable fashion 25 according to the character of stitch formation employed. As shown in Fig. 6 the point of needle emergence from the base layer may be so located with respect to the edge that in the finished product the edge wholly over- 30 lies the points of emergence, and the keying connections, of the penetrant loops.

Each said penetrant loop preferably lies on a line inclined, when viewed in plan, to the edge of the superimposed layer. The 40 precise angle of inclination may be varied according to the character of the work to be done, an angle of about 15 degrees for instance, giving a very narrow seam and minimized display of thread on the superimposed material, such as is very desirable on certain lining work and the like, but necessarily requiring considerable nicety in the handling of the work to insure a proper relation of the edge of the superimposed material to the very narrow range of operation of the needle; and an angle of larger degree, as 45 degrees, giving a somewhat greater width to the range of needle operation and satisfactorily fulfilling the requirements for other lines of felling in clothing manufacture.

In each of the forms of lock stitch felling seam shown (Figs. 1, 2 and 6) the penetrant loops of needle thread all engage and are keyed by a bobbin thread 13, the thread locks, or points of interloopage of the needle and bobbin threads, being preferably drawn somewhat into the goods to an extent appropriately determined by adjustment of the usual thread tension. As far as the en-

gagement of the overcast loops, to be described, is concerned, however, the location of the thread lock, whether at the surface of the work or buried within the work is unimportant, the series of keyed penetrant loops in any event providing stitches passing into and out of the goods, needle thread running connections between points of stitch-entrance, and keying connections between points of stitch-emergence.

In Fig. 5 the penetrant loops are shown as keyed by a second thread 17 in the usual manner of a double thread chain stitch and in Fig. 4 the needle thread loops are interchained so that the stitch-keying chain-connections extend from one point of needle emergence to the next. In each felling seam shown, the keying connections, whether chain loops or bobbin thread, lie along the surface of one layer only of the material and do not cross the edge; and in the constructions specifically shown, wherein the penetrant loops enter the superimposed material back from the edge and penetrate diagonally toward the edge, emerging from the stitched side of the base layer under or adjacent to the edge of the superimposed layer, it is the surface of the base layer whereon the keying connections are exposed. In such construction the keying thread may 95 be wholly or partially concealed as in Fig. 2, the concealing effect being aided by a slight rolling over of the folded edge of the superimposed layer incidentally to the tension on the overcast thread in the machine 100 stitching of the seam, and the rolling may be accentuated by any subsequent pressing operation, the more effectively to cover the bobbin thread. It will be observed in this connection that the diagonal penetration of 105 the superimposed material, having the needle to pass once only through each ply of the superimposed material facilitates such rolling action and enables very successful concealed-effect felling to be produced.

Supplementing the series of keyed penetrant loops of needle thread, which effect the direct interconnection of the superimposed layer with the base layer in each form of felling seam shown, I provide a series of 115 bights or loops in the needle-thread running connections, each springing from two points of entrance of successive stitches into the surface of the work, passing over and across the edge of the superimposed layer, and having its crest or bend positioned on the base layer to embrace the point of emergence of the last made one of said stitches from the work. The overcast bight, so located, engages the emergent portion of the 120 stitch, the crest or bend of the bight underlying, and being positioned by, the running connections between that point of stitch emergence and those next adjacent thereto. Thus, referring to Fig. 1 for example, as

suming the needle to have made its penetrant stroke in laying the first penetrant loop there shown at the right hand end of the figure and to have interlocked with the locking thread and to have withdrawn from the work, the bight of the needle thread 12 is cast over to position partially to encompass the point of emergence on the base layer of the next succeeding stitch; and when the next stitch is formed the needle, carrying a loop of needle thread into and out of the cloth and up through the area circumscribed by the crest in the overcast loop or bight, receives the bobbin thread so that the latter is laid over both limbs of the overcast loop, and when the stitch is set, the bobbin thread, keying the penetrant loop, and generally drawn down through the overcast loop retains the overcast loop in its position embracing the point where the stitch emerges from the surface of the base layer. Such relation of the overcast bights or loops to the keyed penetrant loops does not materially disturb the location or linear extent of the keying thread structure when the tensions are properly regulated, and the setting of the stitch may be performed by the usual takeup action on the needle thread only without necessitating any takeup action on the bobbin thread. This positive location of the bend of each overcast loop restrains the bend against displacement under varying strains upon the seam incident to use; makes for perfect uniformity in appearance and enhances a satisfactory binding effect of the overcast loops upon the edge of the superimposed layer. It will be observed that the structure described gives to the seam an effective penetrant loop for immediate connection of the layers of goods for every stroke of the needle. It will further be observed that the inclination of the stitches to the edge of the goods locates the points of entrance of the needle into the superimposed layer close to the edge in proportion to the length of effective engagement or "bite" of the penetrant loops into the work, so that the limbs of the overcast loops of the needle thread, which are the only thread portions crossing the edge and displayed on the surface of the superimposed material are comparatively short, inconspicuous, and neatly uniform. By the arrangement shown in Fig. 2 a substantial minimum of exposure is attained, and it is in this fashion that commercial concealed effect felling may very advantageously be done.

In Fig. 3 I have illustrated the same form of stitch as that shown in Fig. 1 applied to the connecting of two layers face to face, as in padding. The same advantages of conserving the bobbin thread to avoid unduly frequent replenishment; uniformity of appearance, definite positioning of the over-

cast loops and other advantages are retained but manifestly any concealment of the stitching is not possible nor, in the manufacture of clothing, is there any need for such stitching to be concealed upon the stitched side of the work, as the padding seams are usually covered over with other goods. In such Fig. 7, 20 indicates a superimposed layer which may be of canvas or same other padding material, the points of emergence of the successive stitches being indicated at 21 and each stitch assuming the appearance of a triangle of which the running connection of the keying bobbin thread forms the base and the portions of the needle thread running connections, forming parts of two adjoining overcast loops, and meeting at a point of entrance of a penetrant loop, form the apex.

In all of the forms of hems or seams which are shown in the drawings the penetrant loop of the needle thread forms part of a keyed stitch structure that passes through an overcast loop or bight of the needle thread, having a terminal point in the same stitch and its other terminal point in the preceding stitch.

While I have herein described in some detail particular embodiments of my invention in divers forms of stitch it will be apparent that changes in detail of stitch formation might be made without departure from the spirit of my invention and within the scope of the appended claims.

Having described my invention what I claim is

1. A hem or seam for sewed articles, comprising a plurality of layers of textile or similar material and a row of stitches connecting said layers, said stitches entering and emerging on the same side of the work, consisting of a series of keyed penetrant loop structures, and a series of overcast loops or bights, overcast on the surface of the work from the points of entrance of two successive stitches, the emergent portion of one only of said two successive stitches passing through and engaging the overcast loop formed between it and the preceding stitch, and said overcast loops formed in the same thread as the penetrant loops.

2. A hem or seam for sewed articles, comprising a plurality of layers of textile or similar material and thread uniting said layers of material comprising two series of loops formed in a single thread, alternate loops, constituting one said series being keyed to form stitches penetrating and emerging from the same surface of the work, and the intervening loops constituting the other series being overcast on the surface of the work each from terminal points at the points of penetration of two successive stitches and each said overcast loop embracing the emergent thread at the point of

emergence of the last made one of said stitches and free from the penetrant loops of all other stitches of the series.

3. A hem or seam for sewed articles comprising a plurality of layers of textile or similar material and a row of stitches each entering and emerging from the same surface of the work, said row of stitches consisting of a needle thread and a second thread, the needle thread of each stitch penetrating the material once only and keying with the second thread, and said needle thread also forming for each stitch an overcast loop embracing the emergent thread at the point of emergence of a succeeding stitch.

4. A hem or seam for sewed articles comprising a plurality of layers of textile or similar material and a row of stitches uniting said layers of material entering and emerging from the same surface of the work, said row of stitches consisting of a needle thread and a second thread, said needle thread forming two alternating series of loops, one series consisting of penetrant loops and the other series consisting of overcast loops, each of the overcast loops having its terminal points at the points of entrance of successive stitches and its bend or crest embracing the emergent thread at the point of emergence of the last made of said stitches, and said second thread engaging and keying all of the penetrant loops and overlying and retaining all of the overcast loops.

5. A hem or seam for sewed articles comprising a main layer of textile or similar material and one or more superimposed layers secured to said main layer by a row of stitches entering and emerging from different points on the same side of the goods composed of a needle thread and a second thread, the emergent portion of each stitch engaging with a loop of the needle thread brought forward from the preceding stitch, said needle thread having, in each stitch, a single penetrant loop engaging all of the layers of material and being keyed by the second thread.

50. 6. A hem or seam for sewed articles comprising a base layer of fabric, a superimposed layer, presenting an edge upon the base layer and a row of stitches felling said edge to said base layer, consisting of a series 55 of keyed penetrant thread loops, each said stitch entering and emerging from the same surface of the work and penetrating through the superimposed layer from face to face thereof and into and out of the same surface of the base layer emerging adjacent to the edge of the superimposed layer, and a series of overcast loops formed in the same thread as the penetrant loop each overcast upon the surface of the work from the points 60 of entrance to two successive stitches into

the superimposed goods and engaging the emergent portion of one only of said stitches, at its point of emergence from the base layer, and the emergent portion of each stitch so engaged passing through the overcast loop formed between said stitch and that next preceding it.

7. A hem or seam for sewed articles comprising a base layer of textile or similar material and a superimposed layer presenting an edge upon the base layer and a row of blind felling stitches uniting said base layer and superimposed layer, consisting of a series of keyed penetrant loop-structures entering the superimposed layer and emerging 70 from the base layer on the same side of the work and having a keying connection running along the base layer of material substantially parallel with and close to the edge of the superimposed layer, and a series of 75 overcast loops formed in the needle thread alternating with said penetrant loops and each overcast from the points of entrance of two successive stitches with its bend or crest embracing the emergent thread at the point of 80 emergence of one of said stitches and free from engagement with the penetrant loops of all other stitches of the series.

8. A hem or seam for sewed articles comprising a base layer of textile or similar material and a superimposed layer presenting an edge; of a row of felling stitches securing said edge to the base layer, each stitch being passed, at an inclination to the edge, through the superimposed layer and into 95 and out of the base layer to enter and emerge on the same stitched side of the work and each stitch comprising a keyed penetrant loop; and a series of overcast loops formed in the needle thread, each of said overcast 100 loops springing from the points of entrance of two succeeding stitches and embracing the emergent thread at the point of emergence of one of said stitches and free from 105 the penetrant loops of all other stitches of the series.

9. A seam for sewed articles comprising a plurality of layers of textile or similar material and a row of blind stitches connecting said layers, comprising a needle thread and a second thread, said needle thread having alternating penetrant and overcast loops formed therein, the penetrant loops engaging the second thread to be keyed thereby and to form therewith stitches entering and emerging from the same side of the work, and each overcast loop extending from points of entrance of two successive stitches around the emergent thread at the point of emergence of the second of said stitches under said second keying thread.

10. A blind stitch felling seam comprising a main layer of fabric, a superimposed layer presenting an edge on said main layer, and thread extending in overcast loops in a sin- 110

gle zig-zag course between points upon the upper surface of the superimposed layer near the edge to points upon the main layer near the edge, the remainder of the thread being formed into loops penetrating said layers and keyed, independently of the overcast loops, with the keying connections lying along and beneath the edge.

In testimony whereof, I have hereunto set my hand and affixed my seal in the presence 10 of the two subscribing witnesses.
